PATENTED JAN. 7, 1908.

D. FIALCOFSKY.
CORK EXTRACTING DEVICE.

APPLICATION FILED JAN. 28, 1907.

2 SHEETS—SHEET 2.

UNITED STATES PATENT OFFICE.

DANIEL FIALCOFSKY, OF SOREL, QUEBEC, CANADA.

CORK-EXTRACTING DEVICE.

No. 876,049.

Specification of Letters Patent.

Patented Jan. 7, 1908.

Application filed January 28, 1907. Serial No. 354,576.

To all whom it may concern:

Be it known that I, DANIEL FIALCOFSKY, a subject of the King of Great Britain, residing at Sorel, county of Richelieu, in the Province of Quebec, Canada, have invented certain new and useful Improvements in Cork-Extracting Devices; and I do hereby declare that the following is a full, clear, and exact description of the invention, such as will enable others skilled in the art to which it appertains to make and use the same.

My invention relates to cork extractors; the object of my invention is to provide an extractor which may be actuated into and which will remove a cork by moving the handle of the extractor in one direction; a further object is to provide an extractor which will hold the extracted cork until the movement of the handle is reversed; a further object is to provide means coöoperating with the handle which will cause rotation of a corkscrew forming part of the extractor when the handle is actuated in one direction, which will permit movement of the corkscrew without rotation, and which will again rotate the corkscrew to withdraw it from the cork; and, my invention consists of the construction, combination and arrangement of parts, as herein illustrated, described and claimed.

In the accompanying drawings, forming part of this application, I have illustrated one form of embodiment of my invention, in which drawings similar reference characters designate corresponding parts, and in which:

Figure 1 is a side elevation; and, Fig. 2 is a front elevation. Fig. 3 is a side elevation of the device when the screw has been driven full into the cork. Fig. 4 is a view from the opposite showing the parts just before stripping. Fig. 5 is a view from the same side as Fig. 3 showing the parts when the cork has been fully withdrawn. Fig. 6 is a cross section on line 6—6 of Fig. 1. Fig. 7 is a top plan view of the screw carrier, the screw head and pins being shown in dotted lines, and adjacent portions of the frame in sections, and Fig. 8 is a front elevation of the parts shown in section in Fig. 6.

Referring to the drawings, 1 designates a metallic body having a bifurcation 2 surrounded by laterally projecting flanges 3 adapted to rest on a fixed support, such as a table. A thumb-screw 4 is disposed vertically through one of the arms of the bifurcation 2, and carries a plate 5 having the calks

6, by means of which construction the body 1 may be firmly attached to a fixed support.

The body 1 is provided with a longitudinal slot 7 extending from its lower end to a point intermediate of its length. The slot 7 is closed by an annular sleeve 8, removably secured by means of the screws 8^a to the lower end of that portion of the body 1, which has therein the slot 7. The sleeve 8 is intended and adapted to receive the upper end of the neck of a bottle from which the cork is to be extracted, and the object in having the same removable is to permit ready access to the slideable parts, which are herein described as being disposed in the slot 7.

The body 1 is provided with a transverse bore 9 adjacent the upper end of the slot 7, which bore is surrounded on one side by a raised boss 9^a. Above the bore 9, the body 1 is provided with a longitudinal guide slot 10. Slidably disposed on one side of the body 1 over the guide slot 10, and extending to the slot 7, is a double rack 11, to which is secured a headed pin 12, which pin extends through the guide slot 10, and locks the rack 11 in slideable engagement with the body 1.

Disposed through the bore 9 is a shaft 13, to which is fixed a segmental gear 14, adapted to engage successively the opposite sides of the double rack 11.

Formed on or secured to the lower end of the rack 11 is a block 15, provided with a recess 16. A cork screw 17 is disposed in the slot 7, and has formed on its upper end a head 18, which is disposed in the recess 16 of the block 15. A split pin 19 is disposed through the block 15, and has its ends disposed under the head 18, so that the cork-screw 17 is free to rotate, but is held from dis- placement from the block 15.

Slidably disposed in the slot 7 is a follower 20, having the end flanges 21 engaging over the walls of the slot 7, so that the follower is free to slide in the slot. The block 20 is provided with a screw-threaded opening 22, through which the corkscrew 17 is disposed, so that movement of the corkscrew with relation to the block 20 will cause rotation of the corkscrew.

A handle 23 is secured to the end of the shaft 13 opposite the segmental gear 14, as by means of the pin 24. The handle 23 is provided with a cam 25, adapted to contact against the upper end of a pawl 26, which is rockably disposed on the pivot 27 carried by the body 1. The lower end of the pawl 26 is

provided with a shoulder 28, adapted to engage the follower 20 and to prevent its upward movement in the slot 7. When the handle 23 has been moved so that the cam 25 no longer engages the upper end of the pawl 26, the pawl is adapted to be moved out of engagement with the follower 20 by means of a spring 29, one end of which is secured to the pivot 27, and the opposite end of which engages the lower end of the pawl. A pin 30 is carried by the body 1, and is adapted to limit the movement of the pawl away from the follower 20.

From the position shown in Fig. 1, if the handle 23 be actuated in the direction indicated by the arrow 31, the segmental gear 14 engages the left-hand or upper side of the double rack 11, and actuates the same downward, and the corkscrew 17 passing through the follower 20 is rotated to engage a cork lying within the sleeve 8. In going through the arc of a circle of approximately one hundred and eighty degrees, the cam 25 rides on the upper end of the pawl 26, and the follower 20 is maintained in its locked position. Further movement of the handle in the same direction carries the cam 25 past the upper end of the pawl 26, so that the spring 29 actuates the pawl from engagement with the follower 20, and when in this position, the segmental gear 14 engages the right-hand or lower side of the double rack 11, and actuates the same upward, carrying with it the corkscrew 17 and the follower 20, so that the corkscrew is not rotated and the extracted cork is drawn into the slot 7, where it is held, and the operator is free to use both hands. Movement of the handle from the last described position in an opposite direction, causes the segmental gear 14 to engage the right-hand side of the double rack 11, and forces the corkscrew 17 and the follower downward without rotation of the corkscrew until the cam again contacts with the upper end of the pawl 26, and the follower is locked, and then continued movement of the handle 23 in a direction opposite to the arrow

31 causes the segmental gear 14 to engage the left-hand side of the double rack 11 and actuates it upward, carrying with it the corkscrew 17, and the follower 20 then causes rotation of the corkscrew in an opposite direction to that in which it was rotated when it was first actuated downward. This movement causes retraction of the corkscrew 17 from the cork.

Having thus fully described my invention, what I claim as new, and desire to secure by Letters Patent, is:—

1. A cork extractor comprising the combination of a body adapted to be attached to a fixed support, a double rack slidably disposed on the body, a segmental gear adapted to successively engage the opposite sides of the double rack, a handle adapted to rotate the gear and provided with a cam surface, a corkscrew rotatably supported on the rack, a follower slidably carried by the body through which follower the corkscrew is disposed, and means coöperating with the cam adapted to lock the follower against movement.

2. A cork extractor comprising the combination of a body adapted to be attached to a fixed support, a double rack slidably disposed on the body, a segmental gear adapted to successively engage the opposite sides of the rack, a handle adapted to rotate the gear and provided with a cam surface, a corkscrew rotatably supported on the rack, a follower slidably carried by the body through which follower the corkscrew is disposed, a pawl pivoted to the body having one end disposed in the path of movement of the cam and having the other end provided with a shoulder adapted to engage the follower, and resilient means for retracting the pawl from the path of the follower.

In witness whereof I have hereunto set my hand in the presence of two witnesses.

DANIEL FIALCOFSKY.
